MAGNETIC TAPE HANDLING UNIT

William N. Brownfield, Berwyn, Pa., assignor to Sperry
Rand Corporation, New York, N.Y., a corporation of Delaware

Filed Oct. 22, 1965, Ser. No. 87,815

Term of patent 14 years

(Cl. D26—5)

FIG. 1

The characteristic feature of my design resides in the details of the front panels as best shown in FIGURE 1.

What is claimed is:

The ornamental design for a magnetic tape handling unit, as shown and described.
